United States Patent Office

Des. 187,204
Patented Feb. 9, 1960

187,204

DESK SET BASE

Ronald W. Guttenberg, Chicago, Ill., assignor to The Parker Pen Company, Janesville, Wis., a corporation of Wisconsin

Application December 5, 1958, Serial No. 53,658

Term of patent 14 years

(Cl. D74—1)

Fig. 1 is a front perspective view of a desk set base showing my new design, the broken line illustration of the writing instrument being for illustrative purposes only;

Fig. 2 is a top plan view;

Fig. 3 is a front elevational view;

Fig. 4 is a side elevational view thereof taken from line 4—4 in Fig. 2; and

Fig. 5 is a side elevational view thereof taken from line 5—5 in Fig. 2.

I claim:

The ornamental design for a desk set base, as shown and described.
